ABSTRACT: A closure device for installation in ventilation ducts of protective structures comprising a normally open valve plate mechanically connected to a piston which is blast actuated to pivot the valve plate to a closed position thus effectively sealing the device. A spring assembly maintains the valve plate in a sealed position once it is closed by the blast actuated piston.

BLAST ACTUATED MODULE VALVE

BACKGROUND OF THE INVENTION

1 Field of the Invention

The present invention relates to closure devices for installation in ventilation ducts and more specifically the invention relates to ventilation closure devices which are blast actuated.

2. Description of the Prior Art

Numerous closure devices have been developed for installation in ventilation ducts of personnel shelters to protect against high pressures and shock forces from nuclear blasts. Such devices are activated either by the blast itself or by a mechanism triggered through a sensing unit which responds to phenomena resulting from the nuclear explosion.

The disadvantage of sensor operated closure devices lies in the vulnerability of the sensors to damage and 'false alarms' while the primary disadvantages of existing blast operated closure devices include excessive bypassed overpressure when delay ducts are not employed and excessively long delay ducts when they are used.

The effectiveness of any blast closure device is generally measured in terms of its bypassed pressure pulse or more explicitly by the portion of a blast wave which is allowed to pass through the closure device during the closure operation. There is no prior art device capable of excluding a bypassed pressure pulse but the problem is circumvented by the use of delay ducts. The length of the delay duct then becomes a measure of the efficiency of the closure device since the length of the delay duct can be decreased with accompanying decreases in the closing time of the device. With the present invention, however, a very rapid closure time is effected providing for complete exclusion of the blast wave with only a very short delay duct. Moreover, if a slight bypassed pressure pulse can be tolerated the closure device may be directly blast actuated with complete absence of any delay duct thus providing for the first time a blast actuated closure apparatus in which delay ducts form no significant part thereof.

SUMMARY OF THE INVENTION

The present concept is directed to a closure device for incorporation into ventilation ducts of protective shelters to protect personnel and equipment therein from the effects of a nuclear blast. Moreover the present device maintains the air at atmospheric pressure during the negative pressure phase following any nuclear blast by remaining closed until such time as the device is required to be reopened.

Briefly the blast closure device of the present invention comprises a short conical tube in which is operatively mounted a piston with a mechanical linkage to a valve plate. Most of the blast wave which moves into the ventilation duct, referred to hereinafter as the primary portion, enters the conical tube and impinges on the piston which urges the valve plate to a closed position against a valve seat thus sealing the shelter against either external high or low pressure air. A spring assembly and cooperating pushrod assists in the closure of the valve plate once the blast has actuated movement thereof.

A delay duct is normally incorporated into the ventilation system and is adapted to receive that portion of the blast wave which did not enter the conical tube and referred to for descriptive purposes as the secondary portion of the shock wave. The delay duct is of such length that the secondary portion of the blast wave will not arrive at the present blast device until after it has been closed by the primary portion of said blast wave in a manner described above. However, if a slight bypassed pressure pulse can be tolerated, the delay duct may be completely omitted as part of the device.

STATEMENT OF THE OBJECTS OF INVENTION

One object of the present invention, therefore, is to provide means for very rapid closure of ventilation ducts within protective shelters so as to protect the personnel and equipment therein against the effects of a nuclear blast.

A further object of the invention is to provide a blast operated ventilation duct valve which seals the duct to both high and low pressure phases of a nuclear blast.

Another object of the invention is to provide a blast actuated ventilation duct valve having a relatively short delay duct incorporated therein.

An additional object of the invention is to provide a simple, economical and reliable blast operated ventilation duct valve.

Other objects, advantages and novel features of the invention will become apparent from the following detailed description of the invention when considered in conjunction with the accompanying drawings.

BRIEF DESCRIPTION OF THE DRAWINGS

FIG. 1 is a perspective diagrammatic view partly broken away of a preferred embodiment of this invention.

FIG. 2 is a vertical sectional view of a device embodying the principles of the present invention.

FIG. 3 is a horizontal sectional view along the line 3-3 of FIG. 2.

FIG. 4 is an enlarged vertical section through one spring assembly showing the structure in detail.

FIG. 5 is a diagrammatic view of a ventilation system incorporating the device of the present invention.

DESCRIPTION OF THE PREFERRED EMBODIMENT

The blast actuated valve of the present invention may readily be mounted in a modular relationship within a ventilation duct either singly or in parallel banks. With reference to FIGS. 1 to 3 a single valve assembly comprises a valve housing 10 having end flanges 12, sidewalls 14, top plate 16 and bottom plate 18. A series of spaced parallel reinforcing ribs 20 are positioned about the exterior of housing 10 and are attached to each of the end walls 12, as well as to their adjacent or bottom plate 16 or 18. Similarly spaced parallel ribs 22 may extend transversely across the exterior of housing 10 at right angles to ribs 20 and be attached to each sidewall 14 and also the adjacent top plate 16 or bottom plate 18. At their points of intersection ribs 20 and 22 may be secured to each other.

A conical shaped duct or shock catcher 24 is mounted on the top plate 16 by the boss 26 as shown in FIGS. 1 and 2 and is adapted to receive most of the blast wave (i.e., the primary portion of a blast wave) within the outer expanded portion 28 thereof. The conical configuration of the shock catcher is designed to direct the full force of the blast wave captured within the expanded portion 28 into the throat section 30 where it strikes a flat circular piston 32 movably positioned therein.

Piston 32 is supported on the upper end of piston rod 34 which slides up and down within bushings 36 and 38. Both the piston 32 and piston rod 34 are adapted for immediate response to the blast wave focused within the shock catcher.

24. A plate actuating cam 40 is operatively attached to the piston rod 34 within housing 10 and transmits any movement thereof to a rectangular shaped valve plate 42 which is mounted within housing 10 and hingedly connected to a valve seat 44 along the rear edge 46. The valve plate 42 is then adapted to move rapidly in a pivoting motion toward valve seat 44 thus closing the valve and protecting the ventilation duct in which it may be mounted against any harmful high pressure shock waves.

63 pressure shock waves.

A series of valve plate reinforcement elements 48 are mounted on the upper surface of valve plate 42 in spaced relationship and are integrally connected to a transverse shaft 51 mounted in the opposed sidewalls 14 of housing 10 thus holding 70 the hinged edge of both valve plate 42 and of valve seat 44 in a suitable pivotal position.

During normal operation the valve is open. In this respect valve plate 42 is held in an open position by a pair of spaced parallel spring assemblies 50 mounted within housing 10 in front of valve plate 42 and by a pair of cooperating pushrods 75

52 which are each operatively positioned at one end relative to each spring assembly 50, while the opposite end is pivotally connected at 54 to the forward portion of valve plate 42 in a manner substantially as shown in the drawing. However as soon as the valve plate 42 is actuated, the spring assemblies 50 and pushrods 52 will aid in the closure operation by snapping the valve plate 42 against the valve seat 44.

Each spring assembly 50, shown best in FIG. 4, includes a stationary support tube 56, an elongated cam follower sleeve 58 slidably supported therein and a hollow spring encompassing quill 60 which telescopes into sleeve 58 when the spring 62 is compressed. As shown quill 60 has an enlarged head 63 which has a central depression 65 preferably conical in shape.

The closed end 67 of cam follower sleeve 58 is contiguous to spring relief cam 64 which in turn is mounted on cam shaft 66 transversely positioned and rotatably supported in opposed sidewalls 14.

The opposed end of quill 60 is adapted to receive the forward end of pushrod 52 in the central depression 65 while the spring 68 positioned within the interior thereof serves through rod 52 to maintain constant pressure against the valve plate 42 thus in effect keeping the valve plate open, or when tripped by the blast wave, snapping it closed.

The spring assemblies 50 have several functions. They hold the valve plate 42 open during normal operation. They provide a significant closure force component. When closure is effected, they maintain a seal between valve plate 42 and valve seat 44 and they prevent a premature opening during the negative pressure phase following a nuclear blast.

To reopen a closed valve, shaft 66 is rotated with a suitable crank or tool applied over one of the squared ends 69. Spring relief cams 64 are then rotated to the low point which allows cam followers 62 to ease thus removing spring pressure from rods 62. Thereupon valve plate 42 may be opened from valve seat 44. When valve plate 42 has been pivoted to the open position cam shaft 66 and spring relief cam 64 are again rotated to the position which exerts compression pressure on spring 58 through cam follower 62 thus in effect cocking the valve for future use.

When the major or primary portion of any blast wave from an inlet duct 68 enters the shock catcher 24, a minor or secondary portion of the same wave will enter a delay duct 70 as indicated in FIG. 5. The length of delay duct 70 is predetermined so that the travel time of the secondary portion of the blast wave which enters therein is greater than the travel time of the primary portion which entered the shock catcher 24 plus the time required to close valve plate 42. Thus it is seen that a seal is effected between the delay duct 70 and outlet duct 72 (FIG. 5) prior to arrival at the sealed valve of the secondary portion of the blast wave from the delay duct. It is to be noted that due to the rapid closure of the valve plate 42

against valve seat 44 only a very short delay duct 70 is necessary to completely exclude the blast wave.

As a result of the very rapid closure valve seat 42 against valve seat 44, the use of a delay duct 68 may be completely avoided and the valve directly blast actuated provided a slight bypassed pressure pulse can be tolerated.

If so desired the present valve may be easily amenable to sensor operation. It should be kept in mind, however, that sensor devices are highly vulnerable to explosion characteristics and false alarms.

If the valve seat 44 could be mounted with a solid foundation to which the other structure components could be attached, the valve housing 10 and related structures could be eliminated. Moreover if lightweight flame resistant materials were used in manufacturing the various structural elements of the present valve, an even faster closure time may be realized.

We claim:

1. Means for interrupting the flow of air through a duct when said flow includes a blast wave of predetermined magnitude comprising:
  - a housing forming a part of the duct;
  - a valve seat located within said housing and having an opening through which the ducted air must pass;
  - a valve plate movable from an open position away from said seat to a closed position abutting said seat;
  - a force exerting means linked to said plate;
  - said linkage in a first position urging the plate open away from the seat and in a second position urging the plate closed against the said seat;
  - control means separate from said valve plate acting upon the linkage to shift the plate from the first position to the second position; and
  - said control means being responsive to a blast wave included in the flow of ducted air.
2. The device of claim 1 wherein the force exerting means comprises a resilient spring and the linkage includes a toggle joint.
3. The device of claim 2 wherein the control means acts upon the toggle joint to move the linkage from its first position to its second position.
4. The device of claim 1 wherein means is provided to remove and restore the force exerted by the force exerting means;
  - said means being operable from without said housing.
5. The device of claim 1 wherein the duct has an inlet and outlet and wherein a separate delay duct connects a portion of the inlet duct with the valve housing;
  - said delay duct being of sufficient predetermined length to insure that the portion of shock wave entering therein does not reach the valve housing until the valve plate is closed.
